G. E. ZARING,
COMPOSITION FENCE POST,
APPLICATION FILED NOV. 12, 1912.

1,106,694.

Patented Aug. 11, 1914.

UNITED STATES PATENT OFFICE

GLENN E. ZARING, OF WASHINGTON, IOWA.

COMPOSITION FENCE-POST.

1,106,694.

Specification of Letters Patent. Patented Aug. 11, 1914.

Application filed November 12, 1912. Serial No. 730,919.

To all whom it may concern:

Be it known that I, GLENN E. ZARING, a citizen of the United States, residing at Washington, in the county of Washington, 5 State of Iowa, have invented certain new and useful Improvements in Composition Fence-Posts; and I do hereby declare the following to be a full, clear, and exact description of the invention, such as will enable others skilled in the art to which it 10 pertains to make and use the same.

This invention relates to composition fence posts of the artificial stone type and particularly to the manner of securing line 15 wires to the post.

The object of the invention resides in the provision of a device for securing the line wires to a composition post whereby the said wires will be firmly and securely engaged 20 with the posts through the medium of staples which are adapted to be driven into securing position in a manner similar to that in which they would be applied to an ordinary wooden post.

25 With the above and other objects in view, the invention consists in the details of construction and in the arrangement and combination of parts to be hereinafter more fully described and particularly pointed out 30 in the appended claim.

In describing the invention in detail reference will be had to the accompanying drawings wherein like characters of reference denote corresponding parts in the several 35 views, and in which—

Figure 1 is a front elevation of a fence post constructed in accordance with the invention, a plurality of line wires being shown attached thereto. Fig. 2 an enlarged 40 section on the line 2—2 of Fig. 1. Fig. 3 an enlarged section on the line 3—3 of Fig. 2, and Fig. 4 a fragmental detail perspective view of the staple retaining member.

Referring to the drawings, 10 indicates a 45 fence post formed of cement or other appropriate material molded into shape and having embedded therein during the molding operation a plurality of longitudinal strengthening elements 11. Embedded in 50 and extending longitudinally of the post 10

is a staple retaining member A which is formed from a sheet of metal bent upon itself to produce a tubular member comprising a major portion 12 and a minor portion 13, said minor portion 13 having its 55 sides disposed in convergence and one side bent around the outer edge of the other side as at 14. This staple retaining member A is embedded in and disposed longitudinally of the post 10, one side of said member being 60 disposed in registration with the front face of the post, while the inner or minor portion of the member is bent at an angle to the major portion thereof for a purpose that will presently appear. The side of the 65 staple retaining member which is disposed in registration with the front face of the post 10 is provided with a plurality of spaced openings 15. These openings are at a distance apart equal to the distance apart of 70 the arms of the staples, indicated at 16, which are employed to secure the line wires, indicated at 17, to the post.

In applying the line wires 17 to the post same are engaged between the arms of the 75 staple 16 and the latter then inserted in adjacent openings 15 hammered inwardly. During this operation the outer end of the arms of the staple will engage the angular minor portion 13 of the retaining member 80 and as a result be bent laterally with respect to that portion of the staple arm confined within the major portion 12 of the retaining member. In this manner the staples are efficiently clenched and secured against removal. The efficiency with which the staples 85 16 are secured against removal is enhanced by reason of the convergence of the sides of the minor portion of the retaining member as said sides bind upon the free ends of the 90 staple arms with increasing strength as said staple is driven into the retaining member.

What I claim is:

A composition fence post having a tubular staple retaining member embedded therein with its bore and longitudinal axis running parallel with the longitudinal axis of the post, said retaining member comprising major and minor portions, one side of said major portion being disposed in registration 100

with and forming a portion of the front side of the post and provided with a plurality of equidistantly spaced openings, and the minor portion being bent at an angle to the 5 major portion and disposed in a common plane throughout its extent and having its sides disposed in convergence.

In testimony whereof, I affix my signature, in the presence of two witnesses.

GLENN E. ZARING.

Witnesses:

**J. J. KELLOGG,
HENRY WALDERICH.**
